UNITED STATES PATENT OFFICE.

JOHN S. ALLEN, OF ROCHESTER, NEW YORK.

DESIGN FOR A BICYCLE-FRAME.

45,219.

Specification for Design.

Patented Feb. 10, 1914.

Application filed December 28, 1912. Serial No. 739,124. Term of patent 7 years.

To all whom it may concern:

Be it known that I, JOHN S. ALLEN, a citizen of the United States, residing at Rochester, in the county of Monroe and State of New York, have invented a new, original, and ornamental Design for Bicycle-Frames, of which the following is a specification, reference being had to the accompanying drawing, forming part thereof.

In the drawing: Figure 1 is a side-elevation of a bicycle-frame showing my new de-

sign; and Fig. 2 is a perspective-view, from a position somewhat above and in the rear of the bicycle frame.

I claim:

The ornamental design for a bicycle-frame, as shown.

JOHN S. ALLEN.
